UNITED STATES PATENT OFFICE.

ERNEST N. HUMPHREY, OF NEW BRITAIN, CONNECTICUT.

BELT-BUCKLE.

1,381,122.

Specification of Letters Patent. Patented June 14, 1921.

Application filed March 28, 1921. Serial No. 456,079.

To all whom it may concern:

Be it known that I, ERNEST N. HUMPHREY, a citizen of the United States of America, residing at New Britain, Connecticut, 5 have invented a new and useful Belt-Buckle, of which the following is a specification.

My invention relates to a new and improved belt buckle, the object being to provide a simple and reliable construction 10 which may be easily adjusted and which will grip the belt without injury thereto. These and other advantages will be apparent from a reading of the following description.

15 In the drawings:

Figure 1 is a perspective view of the buckle looked at from the rear, said buckle being open.

Fig. 2 is a horizontal section of the parts 20 as shown in Fig. 1.

Fig. 3 is a similar view with the belt in place and the buckle closed.

Fig. 4 is a perspective view of the several parts of the buckle detached.

25 1 represents the front plate of the buckle body having two corresponding rearwardly extending flanges at the upper and lower opposite edges thereof as indicated at 2—3 respectively, and forming a longitudinal 30 channel or belt passage between them. 4 is a belt gripping plate extending longitudinally of the buckle body and operating as a belt gripping member. This plate 4 is pivoted to the flanges 2—3 at a point near one 35 end of the plate 1. 5 is a lever having a cam shoulder 6 at one end. 7 is a pivot for the lever 5, which pivot secures the said lever to the opposite flanges 2—3 of the buckle body, said pivot being located back 40 of the free end of the belt gripping plate 4, as shown for example in Figs. 2 and 3.

8 represents the belt, one end of which is secured to the lever 5 preferably by means of a clamping lever 9 of any suitable construction. The free end of the belt 8 may 45 be passed into the channel between the gripping plate 4 and the rear of the face plate 1, the belt being entered between these parts adjacent to the pivoted end of the plate 4, which space is sufficiently greater than the 50 thickness of the belt 8 to permit the belt end to be very easily introduced. When the belt end has been pushed entirely through and drawn up to the desired degree of tension, the lever 5 is swung from the position 55 indicated in Fig. 2 to that indicated in Fig. 3, the cam shoulder 6 operating against the free end of the clamping lever 4 so as to force the said lever into tight frictional contact with the belt as shown in Fig. 3. When 60 the lever 5 is straightened out, the strain of the belt end secured thereto holds it in the operative position as shown in Fig. 3. This adds to the security of the buckle.

I claim:

65 A belt buckle comprising an elongated front plate, two rearwardly directed flanges extending longitudinally of the same at the upper and lower edge thereof and forming a belt passage between them, a belt gripping plate pivoted at one end to said flanges near one end of the front plate and at the back of the belt passage, a lever having a cam shoulder coacting with the free end of the gripping plate, said lever being pivoted 70 to said flanges near the opposite end of the front plate, and means for securing a belt to said lever whereby the strain of a belt thereon will hold the lever in the belt gripping position. 75

ERNEST N. HUMPHREY.
